UNITED STATES PATENT OFFICE

91,178

DESIGN FOR A BATHROOM FIXTURE BRACKET

Walter H. Pleiss, Ludington, Mich.

Application May 22, 1933. Serial No. 48,185

Term of patent 14 years

To all whom it may concern:

Be it known that I, WALTER H. PLEISS, a citizen of the United States, residing at the city of Ludington, in the county of Mason and State of Michigan, have invented a new, original, and ornamental Design for a Bathroom Fixture Bracket, of which the following is a specification, reference being had to the accompanying drawing, forming a part thereof.

The figure is a perspective view of a bathroom fixture bracket showing my new design.

I claim:

The ornamental design for a bathroom fixture bracket, as shown.

WALTER H. PLEISS.
